CLAIM

The ornamental design for a horseshoe pad, as shown and described.

DESCRIPTION

FIG. 1 is a top front perspective view of the horseshoe pad mounted to a cuff;

FIG. 2 is a right side elevation view of the horseshoe pad mounted to a cuff;

FIG. 3 is a rear elevation view of the horseshoe pad;

FIG. 4 is a front elevation view of the horseshoe pad;

FIG. 5 is a bottom plan view of the horseshoe pad;

FIG. 6 is a top plan view of the horseshoe pad;

FIG. 7 is a right side elevation view of the horseshoe pad;

FIG. 8 is a left side elevation view of the horseshoe pad;

FIG. 9 is a top front perspective view of the horseshoe pad;

FIG. 10 is a top rear perspective view of the horseshoe pad;

FIG. 11 is a bottom front perspective view of the horseshoe pad; and,

FIG. 12 is a bottom rear perspective view of the horseshoe pad.

The broken lines in the drawings depict a cuff that forms no part of the claimed design.

1 Claim, 10 Drawing Sheets
